UNITED STATES PATENT OFFICE.

ANSON S. RICE, OF BROOKLYN, NEW YORK, ASSIGNOR TO DUPARQUET, HOUT & MONEUSE, OF NEW YORK, N. Y.

ROLL-HEATING DEVICE.

1,343,849.

Specification of Letters Patent. Patented June 15, 1920.

Application filed June 19, 1919. Serial No. 305,275.

To all whom it may concern:

Be it known that I, ANSON S. RICE, a citizen of the United States, and a resident of the city of New York, borough of Brooklyn, county of Kings, and State of New York, have invented a new and Improved Roll-Heating Device, of which the following is a full, clear, and exact description.

The present invention relates to new and useful improvements in roll-warming devices, and pertains more particularly to devices of this character especially adapted for heating or warming rolls in large quantities for use in hotels, restaurants, and the like.

15 The primary object of the invention is to provide a device of this character in which the heat supplied thereto is furnished by a heater of the electric type.

20 A further object of the invention is to construct a device of this character in such a manner that the heated interior is automatically provided with the necessary amount of moisture to prevent drying out of the rolls during the heating operation.

25 A still further object of the invention is to provide means for automatically controlling the moisture within the receptacle.

With the above and other objects in view, reference is had to the accompanying drawings in which—

Figure 1 is a front elevation of the device in the closed position;

Fig. 2 is a vertical sectional view thereof;

Fig. 3 is a similar view taken in a plane at

35 right angles to Fig. 2;

Fig. 4 is a vertical sectional view on the line 4—4 of Fig. 2;

Fig. 5 is a vertical sectional view taken in a plane at right angles to Fig. 4;

40 Fig. 6 is a detail view of the moistening device;

Fig. 7 is a longitudinal sectional view on the line 7—7 of Fig. 6;

Fig. 8 is a detail perspective view of a 45 modified form of the invention.

Referring more particularly to the drawings, the reference character 10 designates a suitable receptacle, the front 11 of which is open and is adapted to be closed by means of a vertically sliding door 12 and a pivoted door 13. The receptacle 10 is supported on a suitable frame 14, the vertical legs of which are braced by means of a shelf 15 and braces 15'.

55 Mounted within the receptacle 10 is a plu-

rality of angle bars 16, which are adapted to form the means by which wire baskets or the like 17 are carried. These angle bars 16 are secured to vertically extending angle bars 18, and said angle bars are spaced from the side walls of the receptacle, as best shown in Fig. 3. Mounted in the bottom of the receptacle is a false bottom 19, which provides means for cleaning the bottom of the receptacle by removing said false bottom 19.

As above stated, the doors 12 and 13 are of the vertically sliding and pivoted type, respectively, and pivotally secured as at 20, to the lower edge of the door 12, is a link 21. Pivoted to the link 21, is a lever 22, which is pivoted at its rear end as at 23. Projecting from the lever 22 in a plane at right angles to the main body thereof, is a crank arm 24, and pivotally secured as at 25, to said crank arm 24, is a lever 26, the forward end of which is pivoted as at 27, to the inner face of the door 13, which in turn is pivoted as at 28.

Pivoted to the lever 22, as at 29, is a 80 downwardly extending lever 30, and pivotally connected as at 31, to the lower end of the lever 30, is a lever 32. The lever 32 is pivoted as at 33, to the bottom braces 15', as best seen in Fig. 2.

It is to be understood that the lever mechanism above mentioned, is duplicated on the opposite side of the machine as shown in Fig. 3.

By this construction it will be seen that as 90 the forward end 34 of the lever 32 is depressed, the several levers 21, 22, 24, 26 and 30 will be operated to slide the door 12 and rock the door 13 to open the device. After pressure has been relieved on the forward 95 end of the lever 34, the same returns to its normal position under the influence of the weight of the reciprocating door 12, and serves to close said door 12, together with the door 13. A dashpot 35 is employed to 100 retard the closing movement of the doors, and eliminate the jarring incident to a quick closing action.

As best seen in Fig. 2, electric heaters 36 are mounted in the space between the angle 105 irons 18 and the outer side walls of the receptacle 10, and extending transversely of the front of the device, is a box 37, by means of which the wires leading to these heaters 36 are inclosed. The front of the box 37 110

is provided with a suitable switch 38 for controlling circuits in the heaters 36. Leading from the rear of the box 37, is a conduit 39, which extends beneath the receptacle 10 to an outlet box 40, as is best seen in Fig. 2.

5 Mounted above one of the heaters 36, is a pan 41, and leading to one end of said pan 41, is a supply pipe 42, the discharge pipe for said pan being located at the opposite 10 end and designated by the reference character 43. Mounted in the bottom of the pan 41, is an absorbent pad 44, the purpose of which will be hereinafter more fully defined.

15 Mounted within the receptacle 10 is a water tank 45, and adapted to supply water to said tank 45, is a pipe line 46, which communicates with a valve 47 more clearly shown in Fig. 4. This valve is automatically opened and closed by means of a float 48, which is pivotally mounted as at 49, and in its pivotal action serves to reciprocate the valve 50 to permit of a flow of water through the passage 51. Leading from the 25 tank 45, is a drain 52, and said drain communicates with a chamber 53, in which is mounted a valve stem 54, the lower end of which is adapted to coact with the valve seat 55 to prevent a flow of water from the 30 chamber 53. The valve stem 54 is maintained in engagement with the seat 55, by means of a spring 56, and to maintain said valve open, the upper end of its stem is provided with a pivoted member 57, which is 35 adapted to be rocked at right angles to the position shown in Fig. 5 for maintaining the lower end of the valve stem 54 out of engagement with the seat 55 as shown by dotted lines in Fig. 5.

40 When the valve stem 54 is disengaged from the valve seat 55, a flow of water through the passage 52, chamber 53 and outlet 58, is permitted, and said outlet 58 communicates by means of a pipe 59, with the 45 pan 41, as designated by the reference character 42 hereinbefore mentioned.

By this construction, it will be seen that water is fed automatically to the pan 41 when the valve 54 is open. The valve 47 is 50 provided with a strainer 60, by means of which impurities in the water are prevented from entering the tank 45, and said tank 45 is further provided with a removable cover 61, whereby access to the interior of the tank may be gained.

The operation of the device is as follows: The several baskets 17 are filled with rolls or like articles to be heated, and are placed upon the angle irons 16 within the receptacle 10. The valve stem 54 is now positioned to permit of a flow of water from the tank 45 to the pan 41. The switch 38 is operated and current is permitted to flow to the heaters 36. As the interior of the receptacle 10 becomes heated, it will be seen that

the rolls will be subjected to said heat, and owing to its position adjacent one of the heaters 36, evaporation of the water contained in the pan 41 is set up to provide the necessary moisture to prevent the rolls 70 drying out under the heating process.

When it is desired to remove the rolls, it is only necessary to exert pressure upon the forward end 34 of the lever 32, and the doors will be operated in the manner here- 75 tofore described.

In Fig. 8, the switch 38 is shown as provided on its stem with a cam member 60'. This cam member 60' is provided with a plurality of peripheral notches 62 in which 80 the upper end of the valve stem 54 may project under the influence of the spring 56 shown.

By such an arrangement it will be apparent that as the electric current is turned on, 85 the flow of water is automatically started to supply the moistening pan 41.

I claim—

1. A device of the character described comprising a cabinet, a heating medium for 90 said cabinet, means for controlling the heat to said heating medium, moistening pans for said cabinet, means for supplying water to said moistening pans, and means for automatically controlling the supply of water 95 to the moistening pans, said means being controlled by the heat-controlling means, substantially as described.

2. In combination with a heating chamber, its heating elements and their control, 100 means for supplying moisture to said chamber, said moisture-supplying means being automatically operated by the controlling means of the heating element substantially as described.

3. In combination with a heating chamber having an electric heating element and a switch for controlling the same, a plurality of moistening tanks, means for supplying water to said moistening tanks, and means 110 operated by said switch for automatically controlling the supply of water to said moistening pans upon operation of said switch.

4. In combination with a heating chamber provided with an electrical heating element and means for controlling the same, of a plurality of moisture pans, means for supplying water to said pans comprising a supply tank, means establishing communication between the supply tank and the moisture pans, and means in said supply line for automatically opening and closing the same upon operation of the controlling means of the heating element and simultaneously therewith.

5. A device of the character described comprising a cabinet, a heating medium for said cabinet, means for controlling the heat to said heating medium, moistening means for said cabinet, means for supplying mois- 130

ture to said moistening means, and means for controlling the supply of said moisture to the cabinet moistening means.

6. A device of the character described comprising a cabinet, a heating medium for said cabinet, means for controlling the heat to said heating medium, moistening means for said cabinet, means for supplying moistening fluid to said moistening means, and 10 means for automatically controlling the supply of moistening fluid to the moistening means.

7. A device of the character described comprising a cabinet, a heating medium for 15 said cabinet, means for controlling the heat to said heating medium, moistening pans for said cabinet, means for supplying moistening fluid to said moistening pans, and means

for automatically controlling the supply of fluid to said moistening pans, said means being controlled by the heat-controlling means and consisting of a cam rotatable thereby for operating a valve in the moistening fluid supplying means.

8. A device of the character described comprising a cabinet, a heating medium for said cabinet, means for controlling the heat to said heating medium, moistening pans for said cabinet, means for supplying moistening fluid to said moistening pans, a valve in 30 said moistening fluid supplying means, and means for simultaneously operating the heat controlling means and the moistening fluid supplying means.

ANSON S. RICE.
